UNITED STATES PATENT OFFICE.

WILLIAM J. PETER, OF NEW YORK, N. Y.

PRESSURE CONTROL FOR HYDRAULIC OIL STORING AND DELIVERING SYSTEMS.

Application filed October 16, 1925. Serial No. 62,925.

This invention relates to hydraulic oil storage and delivery systems and particularly to means for automatically disconnecting the source of pressure when the system is not 5 delivering oil.

In oil storage and delivery systems operated by hydraulic pressure, the oil is stored within a tank and forced out through an oil delivery pipe entering the top of the tank, 10 by means of water forced in at the bottom. Delivery of the oil can be controlled either by means of a valve placed in the water pressure line or a valve placed in the oil delivery line. When such systems are used 15 in gasoline filling stations, the oil delivery pipe passes upward into a meter casing, through the meter, and thence through a delivery hose. The delivery of gasoline in such systems is usually controlled by means 20 of a valve placed in the nozzle of the hose. This method of control finds favor with the operators of filling stations because of its simplicity and directness; it has this disadvantage, however, when the operator completes 25 a given filling job, closes the nozzle, and hangs the hose up, the system, being still connected with the water supply, is under full hydrostatic pressure, and, in the event of a break in the oil delivery line, this 30 constantly acting pressure will act immediately to empty the tank of gasoline. Because of the fire risk thus involved, the authorities in some localities insist that the connection with the operating water supply 35 be closed when the system is not in use. This means that every time the station is used the valve in the water line must be opened, and closed again when the delivery has been completed. The operator must 40 therefore manipulate two controls instead of one, and this, from his point of view, is objectionable. At present, therefore, the valve in the water line is manipulated just twice a day—opened in the morning and closed at 45 night.

In accordance with the present invention I have provided means for automatically controlling the connection between the operating water supply and the tank so that 50 every time the hose is hung up after use this connection is automatically closed. Preferably the connection is automatically opened when the hose is taken down for use. In this way the operator need give no 55 thought to the valve in the water line, but

can confine his attention wholly to the nozzle valve. At the same time the connection with the water supply is completely cut off when the system is not in use, and the danger of a continuing flow of gasoline, following a possible break in the oil delivery line, 60 is eliminated.

I have attained this result by making use of a solenoid which, when energized, opens a control valve in the water line and when 65 de-energized permits this valve to close under the action of gravity or other counter-acting force. In order to energize and de-energize this solenoid at the proper time I place within the meter casing a pivoted hook 70 for the hose, which hook controls a switch in series with the solenoid and a suitable source of electrical energy. When the hose is not in use it is hung upon this hook where its weight swings the hook to open 75 the switch and de-energize the solenoid, so that as long as the hose remains upon the hook the water control valve is closed. As soon, however, as the hose is removed from the hook preparatory to being used, the hook, 80 being properly counterweighted, swings to close the switch, energize the solenoid and open the water control valve.

As a further precaution against fire I provide the counterweight for the hook with 85 a fusible link which, in the event of fire, would melt, releasing the counterweight, and permitting the hook to swing under its own weight to open the switch and de-energize the solenoid.

In accordance with the present invention, I also employ a non-sparking switch to open and close the solenoid circuit, preferably one of the mercury type. By the use of such a switch, the fire hazard arising from the 90 use of switches which spark on make and break is eliminated.

In the accompanying drawings, I have 100 illustrated a preferred embodiment of my invention. In these drawings, Figure 1 is a diagrammatic elevation of a gasoline filling station equipped with the pressure control of the present invention, Figure 2 is a detailed view of the pivoted hose supporting hook mounted in the meter casing, illustrating 105 also the control switch and counterweight, and Figure 3 is a detail of the mercury switch used to open and close the solenoid circuit.

Referring first to Figure 1, 1 represents 110

the storage tank of the system, 2 the oil inlet pipe, 3 the oil discharge pipe and 4 the water delivery pipe. The hydraulic pressure under which the system operates is maintained by a riser 5 terminating in a float box 6 which receives water from any suitable source as, for instance, the city water mains, the level of the water in the float box being maintained constant by means of a float actuated control valve 7. The tank is connected to the sewer through a waste pipe 8. The riser 5 and the sewer pipe 8 are selectively placed in communication with the pipe 4, and hence with the tank, by means of a manually controlled two-way valve 9. This is the main water valve and is usually manipulated only in the morning and night or when the tank is to be filled with oil through pipe 2 and its water discharged to the sewer. During normal operation of the system in dispensing oil, the valve 9 is so positioned that the riser 5 is in communication with the tank through the pipe 4, and communication with the sewer pipe 8 cut off. The oil discharge pipe 3 may supply a plurality of outlets, as illustrated, but as the operation of all is identical I shall describe only one. The pipe 3 passes upward into a meter casing 12 through a meter 13 and terminates in a hose 14 provided with a valve-controlled nozzle 15. The foregoing constitutes what is commonly known as the constant head hydraulic system and of itself forms no part of the present invention. I shall now describe the means whereby the connection with the water supply is automatically opened and closed at the proper times.

In the riser 5, between the float box 6 and the valve 9, I place a control valve 10 provided with a valve rod 11 to which is connected the core of a solenoid 16. This solenoid is in series with a suitable source of electrical energy 17 and a switch 18 mounted within the meter casing. When this switch is closed the solenoid is energized and the valve 10 is opened; when the switch is opened the solenoid is de-energized, and the valve 10 is closed by the action of the valve rod 11 dropping under its own weight. I shall now describe the operation of the switch 18.

A hook arm 19 is pivotally mounted at 20 within the meter casing. One end of this arm terminates in a hose supporting hook 21 normally heavy enough to hold the arm in horizontal position against a stop 22. The other end of the arm is provided with a depending counterweight 23 which overbalances the weight of the hook and tends to swing the arm into the broken line position against a stop 24, but this tendency is overcome by the weight of the hose as long as it hangs upon the hook. The switch 18 is mounted upon the short end of the arm.

The switch illustrated is a non-sparking mercury switch designed to be opened when the arm is in a horizontal position, but closed when the hook is removed and the arm swung into inclined position. It comprises a glass tube having a long leg 25 and a short leg 26 disposed at an angle to the long one but in the same vertical plane. The tube is partly filled with mercury; enough to fill the long leg when horizontal but not enough to fill the short leg at the same time. Lead wires 27 and 28 which are in the solenoid circuit enter the tube through the ends of the long and short legs respectively. The length of these wires within the tube is such that when the long leg is horizontal, wire 28 does not contact with the mercury, but when the switch is tipped, so that the mercury level rises in the short leg, it does. Wire 27 is long enough to remain immersed in the mercury at all times.

In order to permit expansion of the liquids in the tank when the valve 10 is closed I provide a vent pipe 29 extending from a point in the riser between the valve 10 and the tank, to a point immediately above the float box.

The system operates as follows: When oil is to be delivered, the operator removes the hose from the hook, whereupon the weight swings the hook arm upward against the stop 24 and closes the switch which, in turn, closes the solenoid circuit, energizes the solenoid and opens the valve 10. The system is then under the hydrostatic pressure of the water in float box 6 and riser 5, and will deliver oil when the nozzle valve is opened. When the desired quantity of oil has been dispensed, the operator closes the nozzle valve and returns the hose to the hook, whereupon the hook arm is swung downward into horizontal position, the switch is opened, the solenoid de-energized, and the valve 10 closed.

It is to be noted that the actual pressure on the tank when not in use is determined by the position of the valve 10, if above the nozzle 15. Thus, if this valve were placed immediately below the float box the tank would be under the pressure of the riser head at that point which head might or might not be balanced by atmospheric pressure. In any event by cutting off the source of pressure, the pressure of the residual water in the riser could be exerted only momentarily and hence would not be objectionable. It would be quite possible to do away with the valve 10 and operate the valve 9 by means of the solenoid, as illustrated in my copending application, Serial No. 62,926 filed concurrently herewith. But by using a separate control valve 10 it can be placed nearer the float box, thus reducing the pressure upon it and thereby making it easier to operate.

- This system of automatic control depends for its effectiveness upon the fact that the operator will naturally hang the hose upon the hook 21 at the conclusion of each filling 5 operation, there being no other place for him to hang it. Should, however, the operator, through an excess of carelessness fail to return the hose to the hook, or if, for some reason it should become displaced, I have 10 provided a safety device which, in the event of fire, would automatically close the valve 10 and cut off the pressure from the tank. The counterweight 23 is provided with a fusible link 30 which melts at a predetermined 15 temperature, releasing the weight, and enabling the overbalanced hook arm 19 to resume its horizontal position and thereby close the valve 10.
- I claim:
- 20 1. In a hydraulic oil storage and delivery system, the combination of a tank, an oil delivery hose receiving oil from the tank, a source of hydraulic pressure designed to be connected with and disconnected from the 25 tank, a support for the hose when not in use, and means controlled by the support for disconnecting the source of pressure from the tank when the hose is on the support.
2. In a hydraulic oil storage and delivery 30 system, the combination of a tank, an oil delivery hose receiving oil from the tank, a source of hydraulic pressure designed to be connected with and disconnected from the tank, a support for the hose when not in 35 use, means controlled by the support for disconnecting the source of pressure from the tank when the hose is on the support and connecting the source of pressure with the tank when the hose is removed from the 40 support.
3. In a hydraulic oil storage and delivery 45 system, the combination of a tank, an oil delivery hose receiving oil from the tank, a pipe for conducting water under pressure to the tank, a valve in the water pipe, a support for the hose when not in use, and means controlled by the support for opening the valve when the hose is removed and closing the valve when the hose is replaced.
- 50 4. In a hydraulic oil storage and delivery system, the combination of a tank, an oil delivery hose receiving oil from the tank, a pipe for conducting water under pressure to the tank, a valve in the water pipe normally 55 closed, a solenoid acting when energized to open the valve, a support for the hose when not in use and means controlled by the support for energizing the solenoid when the hose is removed and de-energizing it when 60 the hose is replaced.
5. In a hydraulic oil storage and delivery 65 system, the combination of a tank, an oil delivery hose receiving oil from the tank, a pipe for conducting water under pressure to the tank, a valve in the water pipe normally
- closed by a constantly acting force, a solenoid acting when energized to oppose the force and open the valve, a pivoted hook arm for supporting the hose when not in use, a switch operated by the hook, said switch being open 70 when the hose is on the hook and closed when the hose is removed, and a circuit including the solenoid, a source of electrical energy and the switch, the arrangement being such that when the switch is open the solenoid is de-energized and the valve closed.
6. In a hydraulic oil storage and delivery system, the combination of a tank, an oil delivery hose receiving oil from the tank, a pipe for conducting water under pressure to 80 the tank, a valve in the water pipe normally closed by a constantly acting force, a solenoid acting when energized to oppose the force and open the valve, a pivoted arm having a 85 hose supporting hook on one end overbalanced to remain normally in horizontal position, a counterbalancing weight acting constantly to swing the arm and raise the hook but insufficient to overcome the weight of the hose when on the hook, a switch operated by the arm, said switch being open when the hose is on the hook and the arm is horizontal, and closed when the hose is removed and the hook raised, a circuit including 90 the solenoid, a source of electrical energy and the switch, the arrangement being such that when the switch is open the solenoid is deenergized and the valve closed, and a fusible link connecting the counterbalancing weight with the arm. 95
7. In a hydraulic oil storage and delivery system, the combination of a tank, an oil delivery hose receiving oil from the tank, a source of hydraulic pressure designed to be connected with and disconnected from 100 the tank, a support for the hose when not in use, means controlled by the support for disconnecting the source of pressure from the tank when the hose is on the support, and thermally operated means for disconnecting 105 the source of pressure when the hose is not on the support. 110
8. In a hydraulic oil storage and delivery system, the combination of a tank, an oil delivery hose receiving oil from the tank, a source of hydraulic pressure designed to be connected with and disconnected from the tank, a support for the hose when not in use, a non-sparking switch operated by the support, and means controlled by the switch 115 for disconnecting the source of pressure from the tank when the hose is on the support. 120
9. In a hydraulic oil storage and delivery system, the combination of a tank, an oil delivery hose receiving oil from the tank, a pipe for conducting water under pressure to the tank, a valve in the water pipe normally closed, a solenoid acting when energized to open the valve, a pivoted hook arm 125
- 130

- for supporting the hose when not in use, a non-sparking mercury switch operated by the hook, said switch being open when the hose is on the hook and closed when the hose is removed, and a circuit including the solenoid, a source of electrical energy and the switch, the arrangement being such that when the switch is open the solenoid is de-energized and the valve closed.

5 10. In a hydraulic oil storage and delivery system, the combination of a tank, an oil delivery pipe receiving oil therefrom, a meter casing into which the oil delivery pipe passes, a pipe for conducting water under pressure to the tank, a valve in the water pipe, a solenoid acting when energized to open the valve, and a non-sparking switch in the meter casing controlling the energization of the solenoid.

10 15. In an oil storage and delivery system, the combination of a tank, an oil delivery hose receiving oil from the tank, a source of pressure designed to be connected with and disconnected from the tank, a pivoted arm for supporting the hose when not in use, a counterweight acting to swing the arm when the hose is removed, means controlled by the arm for disconnecting the source of pressure from the tank when the hose is on the arm, and a fusible link connecting the counterweight to the arm designed to break at a predetermined temperature.

20 25. In a hydraulic oil storage and delivery system, the combination of a tank, a waste pipe communicating with the tank, a valve in said pipe, a riser communicating with the tank, means for maintaining a constant hydraulic head in the riser, a water control valve in the riser above the waste pipe valve, an oil delivery hose receiving oil from the tank, a support for the hose when not in use, and means controlled by the support for closing the control valve when the hose is on the support.

30 35. In a hydraulic oil storage and delivery system, the combination of a tank, a waste pipe communicating with the tank, a valve in said pipe, a riser communicating with the tank, means for maintaining a constant hydraulic head in the riser, a water control valve in the riser above the waste pipe valve, an oil delivery hose receiving oil from the tank, a support for the hose when not in use, means controlled by the support for closing the control valve when the hose is on the support, and a vent pipe communicating with the tank and extending to a point above the riser.

40 45. In an oil storage and delivery system, the combination of a tank, an oil delivery hose receiving oil from the tank, a source of pressure designed to be connected with and disconnected from the tank, a support for the hose when not in use, and means controlled by the support for the hose when not in use, the source of pressure being controlled by the support for disconnecting the source of pressure from the tank when the hose is on the support.

50 55. In a hydraulic oil storage and delivery system, the combination of a tank, an oil delivery hose receiving oil from the tank, a pipe for conducting water under pressure to the tank, a valve in the water pipe, a support for the hose when not in use, and means controlled by the support for the hose when not in use, the valve being controlled by the support for disconnecting the source of pressure from the tank when the hose is on the support.

60 65. In a hydraulic oil storage and delivery system, the combination of a tank, an oil delivery hose receiving oil from the tank, a source of pressure designed to be connected with and disconnected from the tank, a support for the hose when not in use, and means controlled by the support for the hose when not in use, the source of pressure being controlled by the support for disconnecting the source of pressure from the tank when the hose is on the support.

70 75. In a hydraulic oil storage and delivery system, the combination of a tank, an oil delivery hose receiving oil from the tank, a pipe for conducting water under pressure to the tank, a valve in the water pipe, a support for the hose when not in use, and means controlled by the support for disconnecting the source of pressure from the tank when the hose is on the support.

80 85. In a hydraulic oil storage and delivery system, the combination of a tank, an oil delivery hose receiving oil from the tank, a pipe for conducting water under pressure to the tank, a valve in the water pipe normally closed, a solenoid acting when energized to open the valve, a support for the hose when not in use and means controlled by the support for de-energizing the solenoid when the hose is on the support, thereby closing the valve.

90 95. In a hydraulic oil storage and delivery system, the combination of a tank, an oil delivery hose receiving oil from the tank, a pipe for conducting water under pressure to the tank, a valve in the water pipe normally closed by a constantly acting force, a solenoid acting when energized to oppose the force and open the valve, a pivoted hook arm for supporting the hose when not in use, a switch operated by the hook, said switch being open when the hose is on the hook and closed when the hose is removed and the hook raised, and a circuit including the solenoid, a source of electrical energy and the switch, the arrangement being such that when the switch is open the solenoid is deenergized and the valve closed.

100 105. In a hydraulic oil storage and delivery system, the combination of a tank, an oil delivery hose receiving oil from the tank, means for placing the tank in communication with a supply of water under pressure, a support for the hose when not in use and means controlled by the support for closing communication between the tank and the supply of water when the hose is on the support.

110 115. In a hydraulic oil storage and delivery system, the combination of a tank, an oil delivery hose receiving oil from the tank, a pipe for conducting water under pressure to the tank, a valve in the water pipe, a support for the hose when not in use, and means for opening the valve operable when the hose is removed from the support and automatically operated to close the valve when the hose is replaced on the support.

120 125. In a hydraulic oil storage and delivery system, the combination of a tank, an oil delivery hose receiving oil from the tank, a pipe for conducting water under pressure to the tank, a valve in the water pipe normally closed, a support for the hose when not in use, and means controlled by the support for disconnecting the source of pressure from the tank when the hose is on the support.

130

- closed, a solenoid acting when energized to open the valve, a support for the hose when not in use and means for energizing the solenoid and opening the valve operable when
- 5 the hose is removed from the support and automatically operated to deenergize the solenoid and close the valve when the hose is replaced on the support.
21. In a hydraulic oil storage and delivery system, the combination of a tank, an oil delivery hose receiving oil from the tank, a pipe for conducting water under pressure to the tank, a valve in the water pipe normally closed, a solenoid acting when energized to open the valve, a support for the hose when not in use, a switch controlling the solenoid, and means operable when the hose is removed from the support to close the switch, energize the solenoid and open
- 10 the valve, and automatically operated to open the switch, deenergize the solenoid and close the valve when the hose is replaced on the support.
22. In a hydraulic oil storage and delivery system, the combination of a tank, an oil de-
- livery hose receiving oil from the tank, a pipe for conducting water under pressure to the tank, a valve in the water pipe normally closed, electrically actuated means acting when energized to open the valve, a support 30 for the hose when not in use and means for energizing the electrically actuated means and opening the valve operable when the hose is removed from the support and automatically operated to deenergize the electrically actuated means and close the valve when the hose is replaced on the support.
23. In a hydraulic oil storage and delivery system, the combination of a tank, an oil delivery hose receiving oil from the tank, a 35 source of hydraulic pressure designed to be connected with and disconnected from the tank, a support for the hose when not in use, and electrically actuated means controlled by the support for disconnecting the source 40 of pressure from the tank when the hose is on the support.

In testimony whereof I affix my signature.

WILLIAM J. PETER.
